UNITED STATES PATENT OFFICE.

LEON BENEDICTO GLANZER, OF BUENOS AIRES, ARGENTINA.

PANTOMETER APPARATUS.

Application filed May 3, 1920. Serial No. 378,354.

To all whom it may concern:

Be it known that I, LEON BENEDICTO GLANZER, a citizen of the Argentine Republic, residing at Calle Maipu 671, Buenos Aires, 5 Argentine Republic, have invented new and useful Improvements in a Pantometer Apparatus, of which the following is a specification.

This invention relates to a pantometer apparatus for determining the proportions of objects seen from a distance and for facilitating their graphic design, to any scale which may be desired.

As will hereinafter be seen, the pantometer substantially consists of two plates, 15 of any suitable material, one of which, suitably guided, is arranged to slide on the other.

In the lower plate is formed, either by 20 drafting or fretting, a perfect square, at the edges of which and on both faces of the plate are provided scales, related one to the other and based on fractions of prime numbers. The upper or sliding plate is provided 25 with several geometric designs, either formed by drafting or by fretting, also provided with suitably combined scales.

By means of this apparatus, any desired or possible proportions in any rectangle and 30 the degree of angle or direction of any obliques may be determined.

For the better understanding of this description, illustrated detailed drawings have been annexed thereto, wherein:

Figure 1 shows a plan view of a pantometer constructed in accordance with my invention.

Figures 2 and 3 illustrate a plan view of the obverse and reverse, respectively, of the 40 lower plate.

Figures 4 and 5 are similar views of the obverse and reverse of the upper or sliding plate.

In said views, A indicates the lower plate 45 and B the upper or sliding plate.

The plate A is provided on the obverse, confined by one of the sides of the central square, with the scales α and b , the former of which is divided into 4 equal parts which 50 in turn are subdivided in $\frac{1}{2}$, $\frac{1}{4}$ and $\frac{1}{8}$. The scale b within the same total dimensions of the former, is divided into three equal parts and each of these latter is subdivided into $\frac{1}{2}$, $\frac{1}{4}$ and $\frac{1}{8}$. On the reverse of the same 55 plate are seen the scales α' and b' , the first of which being divided, in combination with

the former scales, into five equal parts, each of which has been subdivided into $\frac{1}{2}$, $\frac{1}{4}$ and $\frac{1}{8}$, while the second part or scale b' is divided into one hundred equal parts or fractions, and each of these latter is subdivided into two fractions.

The plate B is provided, on the obverse, with a square E, adapted to be used for the reproduction of small objects situated at a great distance, both sides of the square being provided with scales combined in the same manner as α , α' and b , b' .

F indicates a quadrant, formed with subdivisions so as to constitute five equal fractions.

G is a consecutive quadrant of F, subdivided into three equal fractions and indicating a point S which with S. C. L. indicates one seventh of the development of the circumference.

Reverse, F and G. Scaled graphometer. H, quadrant.

The material employed in the construction of the pantometer may suitably be aluminum, celluloid, papier mâché or other convenient material.

The operation of the pantometer is as follows: For measuring an object situated at a distance, the pantometer is interposed between the object and the eye, and by more or less withdrawing the same therefrom, the largest dimension is made to coincide with the one dimension of the square opening of the frame A; thereupon, the plate B is made to slide to cause the second dimension of the object to coincide with the one which may result between the inner edge of the frame and the inner edge d of the plate, then upon the scale α , b , or α' or b' at points indicated by the edge d and an edge of the frame, the relation existing between both dimensions of the object may be read; or, without moving the plate of the pantometer, by the prolongation of two sides and the diagonal 1 comprised in the pantometer, the proportional rectangle may graphically be reproduced and drawn to any desired size by the parallels at the sides drawn from any point of the diagonal. The obliques may be reproduced in a similar way. By placing the frame of the pantometer parallel to the plane, the oblique is caused to coincide with an angle of the side, C in the frame A, and thereupon, by sliding the plate B till obtaining the rectangle in which said oblique will be comprised as diagonal.

The same principle may be applied with regard to curves and ellipses, by obtaining the dimensions and direction of the quadrant or rectangle within which they are comprised.

In connection with mixed or polycentric lines, the points of tangency are determined by viewing same from a distance through the quadrants F, G or H.

10 On its obverse, F is also designed for subdivision with a circumference formed by five equal parts, and at G, graphic signs are provided for dividing the same into 3, 6 and 7 equal fractions.

15 On the reverse, F, G is provided with a scaled or graduated graphometer.

The pantometer is substantially destined for use by drawing students in academies, professional schools and primary schools, 20 national colleges, high schools and industrial schools, for measuring from a distance the general and partial proportions of objects and the exact inclines of the obliques and curves determined by their quadrants

25 and of the ellipses by their rectangle. In technical offices, the pantometer will advantageously be used as a scale of proportions and for the graphic reproduction of all kinds of angles.

30 I now declare that what I claim as new and desire to secure by Letters Patent, is:

1. An apparatus for determining the proportions of objects seen from a distance and the degrees of inclination of the obliques, 35 comprising a pair of relatively movable slides, one of said slides having a perfectly square opening therein provided with graduations on its opposite edges, the edges of the square opening being adapted to 40 be held so as to bring one dimension thereof coincident with an apparent dimension of the object being observed and the second slide having one edge provided with graduations aligned with the corresponding

45 graduations along the edge of said square opening, said first named edge being adapted to be moved across said square opening, the movement of the second slide being

effected to pick up a second dimension of the said object between the said edge of the second slide and the parallel edge of the square opening, the body portion of said second slide having a series of openings in the shape of geometrical figures provided with graduated edges, whereby the proportions 55 of various shaped objects brought into register with the corresponding lines at the edges of said opening may be determined by the relative position of one edge of said square across a portion of one of said geometrically shaped openings.

2. An apparatus for determining the proportions of objects seen from a distance and the degrees of inclination of the obliques, comprising a pair of relatively movable 65 slides adapted to slide relatively to each other in a straight line, each of said slides having a square opening therein provided with graduations on the opposite edges parallel to the direction of sliding, the transverse edges of said square openings being adapted to be held so as to bring one of said transverse edges coincident with an apparent dimension of the object being observed, said relative movement being effected to pick up a second dimension of the said object 70 between a transverse edge and an edge of the other slide parallel to said transverse edge.

3. An apparatus for determining the proportions of objects seen from a distance, as 80 claimed in claim 2, in which the body portion of one of the slides is provided with a series of openings in the shape of geometrical figures provided with graduated edges, whereby the proportions of various shaped 85 objects brought into register with corresponding lines at the edges of the said openings may be determined by the relative position of one of the transverse edges of the square opening in the other slide across a 90 portion of one of said geometrically shaped openings.

LEON BENEDICTO GLANZER.
